UNITED STATES PATENT OFFICE.

JOHN A. BOEHRINGER, OF NEW YORK, N. Y.

FINGER-TIP PROTECTOR.

1,408,070.

Specification of Letters Patent. Patented Feb. 28, 1922.

Application filed March 18, 1921. Serial No. 453,441.

To all whom it may concern:

Be it known that I, JOHN A. BOEHRINGER, a citizen of the United States, residing at New York, in the county of New York 5 and State of New York, have invented certain new and useful Improvements in Finger-Tip Protectors, of which the following is a specification.

This invention relates to improvements 10 in finger guards and is particularly adapted for use on the fingers of a sewing machine operator to avoid injury from a needle.

The principal object of the invention is to provide a device which may be easily 15 slipped over the end of the finger in such a position as to completely cover the nail and the tip of the finger and yet leave the finger cushion uncovered so that the material being stitched will come in direct contact with 20 the finger cushion, whereby the operator may be guided by the sensation of touch in manipulating the article being sewed.

Another object of the invention is to provide a device which may be easily and 25 cheaply constructed and pressed into proper formation by the use of suitable dies.

Still another object of the invention resides in the provision of a guard constructed in such a manner as to conform to the shape 30 of the finger with its upper portion arranged to follow the contour of the nail so as to provide a means to prevent the guard from slipping too far onto the finger and leaving any portion exposed.

With these and other objects the invention 35 consists in the novel construction, combination and arrangements of parts which will be fully set forth in the following specification, claimed and illustrated in the accompanying drawings, in which:—

Figure 1 is a view illustrating this device in use, and

Figure 2 is a longitudinal sectional view through the guard.

Referring to the drawings in detail the 45 numeral 5 designates in its entirety this improved finger guard which comprises a substantially tubular body 6, open at each end and provided on its upper side and on its 50 rear end with an extension 7 which is arranged to overlie the finger between the first joint and the root of the nail.

The forward edge of the extension 7 is

bent inwardly and downwardly as at 8 to conform to the shape of the finger at the 55 root of the nail, and extending forwardly from the portion 8 is the nail guard 9 which projects forwardly beyond the forward edge of the tubular body 6 and terminates in a downturned shield 10 which overhangs 60 the outer end of the nail and the tip of the finger as shown in Figure 1.

In use the device is slipped over the end of the finger as illustrated with the nail guard 9 lying against the exposed surface of the 65 finger nail and the portion 8 engaging the finger nail at the point where the nail terminates. In this position, it will be obvious that the under side or the cushion of the finger projects through the recess 11 so as to engage 70 the edge of the article to be stitched. Obviously the finger tip and nail will be guarded against injury by contact with the foot or needle of the machine, and yet the sense of touch is in no way interfered with and the 75 user may guide the article being sewed in the ordinary manner.

While in the foregoing there has been shown and described the preferred embodiment of this invention, it is to be understood 80 that certain minor changes, in the details of construction, combination and arrangement of parts may be resorted to without departing from the spirit and scope of the 85 invention as claimed.

What is claimed is:—

As a new article of manufacture, a finger guard for sewing machine operators comprising a unitary metallic body adapted to be engaged upon the first phalange of a 90 finger, the upper rear portion of said body being cut transversely to present an arcuate edge of relatively large radius and the lower rear portion of said body being similarly formed to a lesser radius presenting a relatively narrow band to engage the inner side 95 of the operator's finger, a down turned portion at the outer end of said body adapted to contact with the edge of the finger nail, and a depressed portion formed in said body 100 adapted to overlie the main portions of the nail, said depressed portion blending into the body at a point substantially over the center of said band portion.

In witness whereof I affix my signature. 105
JOHN A. BOEHRINGER.
